Patented Oct. 30, 1956

179,049

ELECTROPLATING UNIT

Roger Amantea, Providence, R. I.

Application February 10, 1955, Serial No. 34,437

Term of patent 3½ years

(Cl. D26—1)

Fig. 1

Fig. 2

Fig. 3

Fig. 1 is a perspective view showing an electroplating unit embodying my novel and ornamental design;

Fig. 2 is a top plan view thereof;

Fig. 3 is an end elevational view thereof.

I claim:

The ornamental design for an electroplating unit, substantially as shown.
